NAIL AND FASTENER

Emanuel Gisondi, Scarsdale, N. Y.

Application July 24, 1941, Serial No. 403,871

8 Claims. (CL 72—118)

This invention relates to securing devices of the type made use of in the erection of building materials and particularly for securing hard wood, soft wood, composition fibre boards or boards made with gypsum and covered with paper or the like to frame walls and ceiling structure of buildings.

This invention provides a novel and improved means to secure large or small boards or panels which are prefabricated or pre-finished. If same are secured with the conventional face nailing, it results in defacing the material and it is objectionable, because, irrespective of the pains-taking and costly labor to touch up the nail-head holes, the appearance is always marred.

The trend in the building construction industry is to erect as large panels as possible to cover exterior and interior walls and ceilings; since these panels in most cases are pre-finished, blind fasteners and the sliding floating fasteners are an absolute necessity.

There is another advantage in fastening materials with the blind fasteners in that when there are no nails in the face of the boards, there is no sound conductibility, thus making this new fastening method sound-proof.

Some of the fasteners of this invention include springy wire hair-pin clips which fit snugly on the stock lumber applied, requiring no nails whatsoever. Attached to this clip is a pressed metal fastener provided with prongs extending in opposite directions, which penetrate the edges of the applied material. The advantages of the device over the conventional manner of nailing are impressive because:

1. The invented clips provide 100% salvage of the material applied and the clips themselves, should same be removed or used temporarily.

2. These clips have four lateral free movements and one springy movement, and possess great advantages for the expansion and contraction to which wood buildings are always susceptible. When expansion and contraction take place in a building where the boards and panels and materials applied are nailed in the conventional manner, numerous objectionable results occur; either the material breaks off at the nailing point or the material itself might warp and distort its plane, because no allowance is possible in the nailing method to compensate for expansion and contraction.

This invention also includes blind fasteners designed for sliding and floating purposes which perform important duties in the building industry. Because of their sliding and floating qual-

ties, they are very well adapted for accurate tight-fitting square edge, tongue and groove, shiplap or any other joint designs that will interlock each other.

5 One object of this invention is to provide blind fasteners or securing devices by means of which the control of expansion or contraction is taken care of; the material applied is not defaced in any shape, form or manner, making construction fastened in this fashion sound-proof.

The fasteners are inexpensive and easily applied with common, ordinary carpenter tools; materials applied with them are 100% salvaged, resulting in an inexpensive, substantial and 15 handsome job. This invention is both important and necessary due to the lack of similar devices in the market.

Further, it is desired to provide securing devices for general utility in the building industry by means of which boards, panels, etc., of any nature whatsoever of any building structure may be rigidly and securely attached to beams or uprights by an operator who stands in front of the supports or on the opposite side.

20 The securing devices contemplated by the present invention may vary rather widely in details of design, but in every instance will include stamped-out, pressed metal fasteners, wire clips and prongs which can either be nailed to structural lumber or snugly fitted. These clips will always have prongs different in designs and bending angle degrees, in accordance with the requirements of the density and thickness of the boards, panels, etc., which are to be fastened.

25 30 35 Within the scope of the invention, numerous types of securing devices may be designed and made use of, in the accompanying drawings, several are illustrated by way of example.

In the drawings:

40 Fig. 1 is a perspective view of a section of lumber, showing one of the improved fastening devices attached to the same; Fig. 2 is a similar perspective view, in which the pronged plate, constituting a part of the fastener, is of slightly 45 different shape; Fig. 3 is another perspective view, showing a fastener with a pronged plate of another shape; Fig. 4 is a face view of a section of lumber to which a sheet metal frame is attached, said frame being utilized for holding a pronged plate; Fig. 5 is a face view of a pronged plate adapted to be held by the frame disclosed in Fig. 4; Fig. 6 is a face view of another pronged plate, which can, like the plate shown in Fig. 5, be either nailed to the lumber or else held in place by either of the frames shown in

Figs. 4 and 7 or by hair-pin clips; Fig. 7 is a front view of a wire frame operative in the manner similar to the sheet metal frame of Fig. 4; Fig. 8 is a perspective view of a section of lumber to which a hair-pin clip is attached and which is holding a pressed metal plate out of which a plurality of prongs have been punched; Fig. 9 is a similar perspective view of a hair-pin clip, showing the same engaging in the rolled-up or tubular edges of a pronged plate; Fig. 10 is a perspective view showing a hair-pin clip having its leg portions formed with pronged terminals; Fig. 11 shows another wire clip of two-part form on which prongs are formed; Fig. 12 is a perspective view of a portion of the wire clip shown in Fig. 11; Fig. 13 is a face view of a pronged fastener plate forming a so-called "blind fastener"; Fig. 14 is a similar view of another fastener plate of the blind type; Fig. 15 is a transverse sectional view through the fastener shown in Fig. 13; Figs. 16 to 18 inclusive are diagrammatic views of several types of prongs adaptable for use in fastening sheet material in place; Fig. 19 is a perspective view of a section of lumber, showing the end portions of the hair-pin clips; Figs. 20, 21, 22 and 24 are perspective views showing four types of plate fasteners provided with prongs of the character shown in Fig. 18; Fig. 23 is a perspective view in section showing how the fasteners of Figs. 1 to 3 operate to hold two pieces of board in position; Fig. 25 shows a fastener adapted to be supported on the lumber by two nails; Fig. 26 is a sectional view through a piece of lumber, showing the application of a fastener of Fig. 14 thereto; Fig. 27 is a diagrammatic view of a special form of prong; Fig. 28 is a perspective view of a portion of a wall, showing a large board applied to the studs by the improved fasteners; Fig. 29 is a sectional view, showing penetration of the prongs into the wall board; Fig. 30 is a sectional view at right angles to that of Fig. 29; Fig. 31 is a face view of the blank from which a sheet metal nail-like fastener is produced; and Fig. 32 is a side view of the finished nail-like fastener.

In Fig. 1 is shown a perspective view of a fragment of lumber or a beam 1, engaged by a wire hair-pin clip 2, said clip being formed of drawn wire of suitable strength and resilience to enable it to securely engage and maintain itself upon the beam. The spaced leg portions of the clip pass through parts of a pressed metal fastener 3, provided with two or more saw-toothed prongs 4 and 5 extending in opposite directions. These toothed prongs are formed on the end of a projecting flange 3a and one of these prongs penetrates and extends into the edge of the board 6 (Fig. 23) for a sufficient distance to furnish more than the minimum of support required for holding the board in position. The prong 5 projecting in the opposite direction penetrates into the edge of the adjacent board 7 and is driven securely therein. Thus, the projecting flange 3a is located between the edges of the two boards and the prongs 4 and 5 extending in opposite directions, project into the edges of said boards. The supporting prongs 4 and 5 of the fastener project substantially at right angles to the flange 3a and thus, when they penetrate into the edges of the board, they extend therein and are located substantially parallel with the outer surface of the lumber 1 and at a sufficient distance from said outer surface and not less than one-half of the thickness of the board used. This clip can be arranged,

by slight modification in design, where necessary, to accommodate boards provided with tongued and grooved edges, or having shiplap joints, or any other type of joints. The sliding wire clip 2 so engages the lumber that the lumber may expand or contract within it, thus resulting in a floating ceiling or wall. Since the metal fastener 3 is vertically slidable on the leg portions of the clip, it will be apparent that movement in both horizontal and vertical directions of the fastening device may be had.

In such cases where it is desirable to permanently and fixedly secure the metal fastener 3 to the lumber, this may be done by omitting the wire clip and using nails extending through the nail holes 8 and entering into the lumber.

In Fig. 2 is shown a perspective view of a section of lumber 1 provided with hair-pin type wire clip 2, the clip being substantially the same as that shown in Fig. 1. The pressed metal fastener 10 has longer projecting end portions 11 and also longer oppositely bent prongs 12 which are necessary to fasten heavier boards or panels in position. Otherwise, the advantages and functions attained by this fastening device are similar to those of the clip disclosed in Fig. 1.

In the embodiment of the invention disclosed in Fig. 3, the hair pin clip 2 extends through the projecting flange 3a of a pressed metal fastener 13 which is substantially H-shaped. Said fastener 13 is provided in its spaced apart leg portions 14a with projecting ridges or ribs 14 protruding to a greater extent than the leg portions of the wire clip 2. These protruding ribs or ridges provide firm contact against the back of any applied material held by the fastener 13, such material, for example, being glass or mirrors cemented on boards. Since the applied material rests against, or rides on, the ribs or ridges 14 in track-like fashion, any slight variations in the shape or positioning of the hair-pin clip 2 does not effect the true plane of the two applied pieces of sheet material, because of the clearance space between the ribs or ridges 14 and the hair-pin clip 2.

Fig. 2 discloses a fragment of lumber 1 with a front view of a sheet metal stamped-out frame 15 applied to the face of the lumber and attached thereto by means of the two spaced nails 19. This frame is adapted for use in holding the fastener 16 such as shown in Fig. 5, or any other similar type of pronged fastener constructed in accordance with this invention. The combination of the frame 15 and fasteners 16 supported thereby, provides a sliding, floating, invisible sheet material fastening means of the so-called "blind" type. By a "blind fastener" is meant one which penetrates into the back face of the panel and clinches over within the panel without penetrating completely through it, and without being discernible from the front face of the panel. The frame 15 is formed with two nail slots 17, said nail slots being widest at their ends so that shifting movement of the frame may not only take place transversely of the beam, but also angularly, if such movement is necessary.

In Fig. 5 is shown a front view of the stamped out pronged blind fastener 16 which can either be nailed on a wood structure member for stationary purposes or it can be used in connection with a stamped-out sheet metal frame such as shown in Fig. 4, or with a wire type such as shown in Fig. 7 and hereinafter described. The several prongs 21, which hereinafter are described in detail, normally extend at approximately 90° to

the body of the fastener and curl or clench over within the applied board. The fastener 16 is provided with two tongues 20 which, when the fastener is used in connection with a frame, such as shown at 15, are bent around the segmentally shaped side members 18 of the frame 15, as shown in Fig. 4, to slidably hold the fastener 16 between the frame 15 and the face of the lumber 1. The segmentally shaped side members 18 permit angular movement of the fastener with respect to the frame. The engagement of the fastener 16 with frame 15 is thus one which permits the fastener to move vertically on the two side members 18 when such movement is necessary.

In Fig. 6 is disclosed a front elevation of a six-pronged blind fastener 22 formed with prongs 21. This fastener can be either nailed on structural framework by nails extending through the holes 8 or it can be used in connection with a sliding, floating wired clip 2 or frame 15. The prongs 23 of this fastener extend at approximately 90° to the body of the plate 22 and as described in connection with the fastener of Fig. 5, these prongs curl or bend over within the body of the sheet material to thereby hold the sheet material in position.

In Figs. 17 and 18 is disclosed prongs similar to those shown in the fastening members of Figs. 5 and 6. These prongs are provided with a number of stepped sections; the wider portion 50 of the prong is situated adjacent to the base or body of the fastener on which the prong is formed. Located at a predetermined distance away from the point of connection of the prong with the base or body of the fastener is a step or shoulder 51 and projecting therefrom is a thinner or narrower portion 52 of the prong which may gradually taper until it terminates in a needle-like point 53. The arrangement of this type of prong is such that in use the needle-like termination or point 53 first penetrates into the wall board and starts to bend over therein. When the wall board reaches the shoulder portion 51 of the prong, a greater resistance to penetrate occurs and a greater binding of the narrower or thinner portion of the prong takes place. The actual point of bend or the narrower or thinner portion 52 is at the shoulder 51. Accordingly, the position of this shoulder with relation to the entire length of the prong is that which determines the extent of penetration of the prong within the wall board. Thus, if it is desired that the prong penetrate for a considerable distance through the board, the shoulder 51 will be located relatively close to the point of joinder of the entire prong with the face portion of the fastener such as shown in Fig. 18. On the other hand, when a relatively deep penetration of the prong into the board is desired, the shoulder 51 or point of bending of the prong will be relatively remote from the point of joinder of the prong to the base portion of the fastener. Thus, the position of this shoulder or of a series of such shoulders which might be used in successive stepped formation, the bending of the prong can be controlled and resultantly the extent to which the prong penetrates into the board is also accurately governed.

The frame 30 is disclosed in Fig. 7 and is similar in operation to that consisting of sheet metal indicated at 15, except that the frame 30 is composed of wire.

In Fig. 8 a hair-pin clip 2 is shown, similar to that shown in Figs. 1, 2 and 3. In embracing a beam or other piece of lumber, the two leg por-

tions of the clip overlie the front face of the beam, and are bent at right angles to extend over an edge of the beam and are then bent down to overlie the rear face of the beam, as shown in Fig. 19, the two leg portions being there connected into U or V shape as indicated at 40 and 41 in Fig. 19. The back portion 40, properly termed a "goose-neck" back for the clip, has the two points of contact, indicated at 42 and 43, against the back of the beam, and since a back of this form protrudes slightly from the back of the beam, it is employed wherever there is sufficient space behind the beam.

The back portion shown at 41 is flat and the same is in complete contact with the back of the lumber. This can be used where there is no space behind the beam for the employment of the type indicated at 40. While the clip 2 is shown as consisting of two spaced connecting leg portions, it is also possible to use single wire types in spaced relation or in groups. Such a single wire type is shown at 44 in Fig. 19 and this type can be used in pairs or in groups of more than two, particularly when placed on a furring strip, generally known in the trade as a "one by two" piece of lumber, and which is nailed on a "two by four" or other structural member. The end of the back leg of the clip 44 is curled and flattened as at 45, to provide a firm bearing against the back of the beam.

In the embodiment of the invention shown in Fig. 8, one of the wire clips 2 is shown, the same carrying a slidable and adjustable plate 46 having its side edges rolled or curled as at 47 to provide guide-ways through which the legs of the wire clip 2 may pass. These guide-ways 47 permit slidable adjustment of the fastener 46 in the manner previously described with respect to the other fastener members. The fastener 46 is provided with punched-out prongs 48, which prongs may be of the form shown in Fig. 16 or else may be of any of the other forms herein described.

In Fig. 9 a plate 46 similar to that shown in Fig. 8 is disclosed. In this embodiment of the invention, however, fastening prongs 49 are in the form of wire staples held by or located behind the fastener plate 46 and protruding through the same and forwardly to penetrate the wall board pressed against them.

In Fig. 10 the legs of the clip 2 are provided with out-turned pointed terminals or prongs 65 which penetrate directly into the wall board.

In Fig. 11 is shown a hair-pin clip 2 provided with two outwardly projecting pointed terminals or prongs 66. This clip 2 has its leg portions extending around three sides of the lumber, said leg portions terminating in a loop 67, seen in Fig. 12. A triangular-shaped piece of wire 68 extends over the two prongs 66 and this is provided with a projecting prong 69 and a hook portion 70 engaging in the loop 67. This is a so-called "blind" fastener and provides three projecting prongs, namely, those shown at 66 and 69, penetrating into the wall board.

In Fig. 13 is shown a front view of a fastener stamped out of sheet metal, the same being provided with two prongs 71 which may be of any of the shapes herein described. These two prongs are adapted to penetrate into the wall board. Extending laterally from the side edges 72 of the plate are fastening prongs 73 which are notched or cut in herringbone formation. These prongs 73 are bent so as to penetrate into the sides of the

lumber or beam and thus fasten the plate to the beam.

In Fig. 14 is shown a front view of another type of blind fastener. This fastener includes a strap portion 74 having pointed ends 75. The strap is bent around the beam as shown in Fig. 26 and the pointed ends 75 are forced into the opposite sides of the beam. The prong portions 76 and 77 are bent forwardly for entry into the wall board.

In Figs. 20, 21, 22 and 24 are shown various types of sheet metal fasteners with prongs bent laterally from the edges thereof, the prongs being of the type shown in Figs. 17 and 18, and previously described. These are examples of several forms in which the fasteners may be made and it will be obvious that the fasteners may also be made in a number of other forms to suit different requirements.

In Fig. 25 is shown a blind clip or fastener which may be held in position by a nail 78. The nail engages in an angular or V-shaped notch 79 and by reason of this arrangement may be inclined or adjusted while one of the prongs 80 is engaged into the edge of one of the boards. The nail may also be entered through the hole 8 and the other prong 81 engaged with the edge of the second sheet of board. This fastener may be solely held by the nail 78 and that entering through the hole 8 or be supported by sliding, floating frames such as shown in Figs. 4 and 7.

In Figs. 31 and 32 is shown a fastening nail composed of pressed metal. In Fig. 31 the blank from which the nail is formed is disclosed, said blank being provided with a central disc shaped portion 82 from which extend the two serrated prongs 83, each of these prongs terminating in point 84. In producing the nail, the two prong portions 83 are bent at right angles to the plane of the disc or head 82 resulting in the finished product shown in Fig. 31. While the nail is disclosed as having two prongs, one or more prongs may be used, the features of the invention being therein included. It is also possible to form the prongs like those shown in Figs. 17 and 18, and by which the extent of penetration of the prongs into the board may be determined. This composite nail is adapted for use in fastening building materials such as wood, composition, sidings, shingles and similar products in building construction. When the nail is applied in place, each blow of the hammer results in the bending and supporting of the prongs 83 both sideways and flat. This is due to the fact that the undulating or notched arrangement of these prongs, such as illustrated at 85 in Fig. 27, permits buckling or bending over at these weakened points. Thus, when these nails or prongs are bent over within the board, it insures a solid grip upon the material.

While I have shown and described a number of embodiments of the invention, it is obvious that various modifications may be made without departing from the spirit of the invention. The primary purpose of the fastening means disclosed is to provide penetrating prongs on a fastener which may be used to securely engage and hold the wall boards by penetration either into the edges of the same or by entrance into the rear face of the same or by bending or curling over within the board without penetration of the opposite face. The invention also contemplates the provision of a penetrating nail-like fastener to be forcibly driven into the boards from the face of the boards for the purpose of attaching other materials to said boards. It also contemplates

the important mounting or support of the clip by which shifting in practically all directions is possible to compensate for expansion and contraction of the beam, as well as to enable the clip 5 to be adjusted to more readily engage the wall board at the points indicated.

What I claim is:

1. A fastener for wall board and similar sheet material comprising a wire clip having leg portions embracing a section of lumber and extending over several faces of the same, a fastener member supported by said clip, said fastener having oppositely disposed prongs for entry into the edges of adjacent sections of sheet material, said fastener being so held by the clip that it is capable of shifting movement thereon, and the clip so engaging the lumber that the lumber can expand or contract within the clip without causing displacement of the clip or material shift of position of the clip.

2. A fastener for wall board comprising a spring wire clip having leg portions embracing a section of lumber between them, a fastener member comprising a sheet metal plate having holes through which the leg portions of the clip extend, said fastener being provided with a projecting flange having its edge formed with oppositely directed prongs, one of said prongs being entrant into the edge of a sheet of wall board and the other prong entrant into the edge of another sheet of wall board, the edges of the two sheets being held in abutment while so engaged by the prongs.

3. A fastener for wall board comprising a sheet metal plate formed with prongs entrant into the wall board, means for attaching said plate to a section of lumber comprising a clip extending at least partly around the lumber and solely secured thereto by its embrace of the lumber whereby said clip may shift bodily relatively to the lumber embraced by it, the engagement of the clip and plate being such that the plate is capable of a sliding movement relative to the clip.

4. A fastener for wall board comprising, a wire clip embracing a beam and held thereon solely by its embrace of the beam, and a pronged sheet metal fastener member slidably held by the clip, said fastener member having several prongs entrant into the wall board.

5. A fastener for wall board comprising a wire clip embracing a beam and having spaced leg portions extending across a face of the beam, a sheet metal fastener having guides slidably received on said leg portions whereby said fastener is adjustable along the leg portions, said fastener having a flange projecting laterally from the face of the beam against which it is held by the clip, said flange terminating in oppositely directed prongs for penetration into the opposite edges of adjacent wall board sections.

6. A fastener for wall board comprising a metal plate formed with prongs projecting in opposite directions for penetration into wall board, means for attaching said plate movably to a beam comprising a U-shaped element embracing the beam and overlying several sides of the same and held on the beam solely by its embracement of the same whereby it may shift its position on the beam under expansion and contraction.

7. A fastener for wall board comprising a metal plate formed with prongs projecting in opposite directions for penetration into wall board, means for attaching said plate movably to a beam comprising a U-shaped element embracing the beam

and overlying several sides of the same in position on the beam solely by its embracement of the beam whereby it may shift its position on the beam under expansion and contraction, said U-shaped element including a resilient arched tongue portion contacting at two points with the face of the beam over which it extends.

8. A fastener for wall board comprising, a wire clip extending at least partly around a beam and capable of shifting movement thereon under expansion and contraction of the beam, and prongs carried by said clip for engagement and support of wall board.

EMANUEL GISONDI.
